PROCESS AND APPARATUS FOR CRACKING
OILS

William F. Moore, Jackson Heights, N. Y., assignor to The Texas Company, New York, N. Y., a corporation of Delaware

Application April 18, 1928, Serial No. 270,817

11 Claims. (Cl. 196—60)

This invention relates primarily to an improved method, and suitable apparatus for carrying out the method, of converting higher boiling oils into lower boiling oils, particularly of the gasoline series. It is a special object of the invention to provide a system of the general character indicated for producing a blended product which is high in its anti-knock characteristics. Various experiments have shown that the cracking of oils in the vapor phase, particularly under certain special conditions, will result in the formation of lighter oils which are relatively high in their anti-knock qualities. This is commonly explained as due to the presence of a larger percentage than usual of unsaturated hydrocarbons in the final product. With this in view, the present invention contemplates a combined liquid and vapor phase system in which a portion of the final product, which is formed by the blending of two separate constituents produced by the system, results from purely liquid phase conversion while another portion of the final mixture results from purely vapor phase conversion. In the course of the process, certain of the heavier components from the vapor phase system will be returned to the liquid phase and may be carried into the final product of this phase. By blending the products resulting from the two distinct phases of the process, a gasoline having the desired high anti-knock qualities is obtained.

The invention is particularly applicable to a system of the type commonly termed coil and drum or tube and tank, although it may readily be applied to other cracking systems as well. Under one specific mode of application of the invention, it is proposed to pass a stream of oil through a heating coil under considerable pressure and then to introduce the oil into a drum or series of drums, or any equivalent enlarged zone, where cracking of the oil may take place in the liquid phase or in the combined liquid and vapor phase, if desired. Vapors which are generated or released within the drums, or any connected expansion chamber, are then led into a fractionating tower, or other dephlegmator, from which the lighter ends emerge as vapors and are collected as a portion of the final product. The bottoms, or condensates, collected in the base of the dephlegmator are then, in accordance with the invention, passed into a zone of reduced pressure where a large portion of these condensates are again vaporized. Vapors so formed may, if desired, be subjected to further fractionation or rectification to eliminate

improperly condensed gasoline constituents and the remainder of this fraction may then be passed into a zone, which may be in the form of a heating coil, where the oil is revaporized and cracking takes place in the vapor phase. Preferably, however, the entire mass of vapors will be passed directly to the coil in the vapor phase zone. From this zone the products are then directed into another fractionating tower, or other dephlegmator, from the top of which the lighter gasoline fraction is taken off, condensed, and collected. The condensates which collect in the base of this dephlegmator, on the other hand, will preferably be combined with the unvaporized portions which collect at the point where pressure is released and this mixture is returned to any suitable point in the liquid-phase cracking system.

To obtain the desired characteristics hereinbefore mentioned, it is contemplated mixing the products resulting from and separately taken off from the liquid phase and vapor phase treatments of the oil.

Many objects and advantages, in addition to those already mentioned, will become apparent from the detailed description of one admirable form of the invention, which will now be given in conjunction with the accompanying drawing, which forms a part hereof.

The single figure illustrates schematically one suitable form and arrangement of apparatus which may be employed in the practice of the invention.

Referring now to the drawing, a fresh charge of oil is admitted to the system through a line 10 and is passed by means of this line to an upper section 11 of a heating coil located in a furnace 12. This section of the coil is preferably located in the upper or cooler portion of the furnace or may be in a separate furnace or enclosure adapted to receive the heated gases generated by the burners employed in the furnace 12. For convenience, this section of the coil may be designated the economizer. From the outlet end of the economizer, the charge is passed into a lower section of the heating coil, which may, for convenience, be termed the pre-heater section and which is preferably located in a hotter portion of the furnace where it may receive radiant heat, as well as the heat of convection, of the flue gases. A transfer line 14 is provided for the purpose of introducing the heated charge, which has been raised to a cracking temperature in the lower section of the coil, into one or more of a series of drums or stills 55.

15. If desired, only a single drum need be provided but it is preferable to employ a series of three or four drums, which are interconnected by lines 16 above the liquid level and lines 17 below the liquid level in the several drums. These drums may be heated from an external source, if desired, or they may be merely heat insulated.

From the last of the series of drums a vapor line 18 is adapted to convey the generated lighter vapors to a suitable dephlegmator or fractionating tower 19, which may, for example, be of bubble tower construction, if desired. In this tower a separation between the lighter and heavier constituents of the vapors will be effected and the lighter constituents will pass out of the top of the tower through a suitable refluxing condenser 20 from which the vapors of desired endpoint pass on through a line 21 to a final condenser 22 and a collection receptacle 23. The heavier constituents of the vapors entering the tower 19 are drawn off from the latter by means of a transfer line 24 and are passed through a reducing valve into a vaporizer drum or expansion chamber 25. Here the greater portion of the condensate withdrawn from the base of the tower 19 will be vaporized under the reduced pressure and will be passed through a line 26 to a separate heating coil 27 preferably located in the same furnace with the economizer section and preheater section of the coil of the liquid phase system. If desired, the coil 27 could be located in a separate furnace, although it is deemed preferable to place it in the same furnace 12 at a point just above the preheater section where the relatively hot gases circulate around its tubes but where no direct flame or radiant heat is present. In the line 26, suitable means, such as fractionator 26', may be provided, if desired, for the purpose of fractionating or rectifying the vapors so as to eliminate any of the gasoline fraction which should have gone over through the condenser 20 but which was knocked back together with heavier components. If this is done, however, it will be necessary to apply additional heat in the coil 27 to revaporize the oil. Reference numerals 42, 43, and 44, indicate valves whereby fractionator 26' may be rendered active or inactive. Refluxing liquid may be supplied to the fractionator in the usual manner through line 48. When the fractionator is in use gasoline fractions pass off from the top thereof through line 45 for any desired treatment, valve 46 serving to maintain the desired pressure in the fractionator, while the condensate collecting in the base of the fractionator passes through line 47 to coil 27. When the fractionator is not in use the vaporized gasoline fractions are passed from the vaporizer 25 through coil 27 wherein they are subjected to cracking in the vapor phase.

From the outlet end of the coil 27 wherein the vapors have been subjected to further cracking in the vapor phase, a line 28 serves to convey the vapors to a suitable dephlegmator or fractionating tower 29. Here the lighter vapors pass on through and are carried out at the top through a refluxing condenser 30 and on to a final condenser 31 and collection receptacle 32. The heavier constituents of the vapors introduced into the dephlegmator 29 will preferably be withdrawn through a line 33 at the base of the tower and passed to a suitable surge pump 34. In a similar manner, the heavier constituents of the condensate withdrawn from the dephlegma-

tor 19, and which are not vaporized in the drum 25, are withdrawn from the latter through a line 35 and also sent to the surge pump 34. This pump then serves to pass both of the streams of oil from the two sources mentioned through a line 36 into the liquid phase system. As shown in the drawing, this is preferably effected at a point in the preheater section 13 of the heating coil where the temperature of the recycled material will be substantially the same as that of the fresh charge which has been passed through the economizer coil. Obviously, if desired, the recycled stock may be introduced at any other suitable point in the liquid phase system. In lieu of a single surge pump 34, it may be found preferable to employ two separate pumps for returning the material withdrawn from the base of the drum 25 and that withdrawn from the base of the dephlegmator 29. A slight difference in pressure will probably be found to exist at these points due chiefly to the friction encountered in the passage of the vapors through the coil 27. Furthermore, the system may be so operated, if desired, as to provide a further drop in pressure between the coil 27 and the dephlegmator 29.

Suitable tar drawing lines 37 will, of course, be provided in connection with the drums 15 for passing the heavier residual oil collecting in these drums to suitable storage. In the line 10, a valve 38 may be provided, if desired, to force the fresh charge through a line 39, a heat exchange coil 40, and a return line 41. In this way the fresh charge may have its temperature raised to a certain extent before it is introduced into the economizer coil and suitable means is provided for regulating the temperature at the top of the tower 19. Obviously, the valve 38 may either be completely open, partially open, or completely closed, to suit the particular conditions. Reference numeral 23' indicates a pipe having control valve 32', by which distillate in the receptacles 23 and 32 may be blended if desired.

In the operation of the system, the temperature and pressure conditions adapted may vary within wide limits. It is contemplated as preferable to operate the liquid phase portion of the system at a substantially uniform pressure throughout, although it is clearly within the scope of the present invention to provide a drop in pressure either between the heating coil and the drums or stills 15, or between the latter and the dephlegmator 19 or at both points. Under any of these modes of operation, the coils 11 and 13 will preferably carry the charge under a pressure of between 100 pounds and 500 pounds, or even higher, if desired. In the vaporizing drum 25 it is contemplated that a pressure only slightly above atmospheric, or possibly up to or slightly above 100 pounds, will be carried and this pressure will preferably be maintained throughout the vapor phase portion of the system, except for minor drops due to friction. Suitable temperatures will be carried in the various sections of the system to effect cracking primarily in the drums 15 and the coil 27, although some cracking may also take place in the coil 13.

While one admirable mode of practicing the invention has been disclosed in detail, it will be understood that it is capable of various modifications without departing from the spirit or scope of the invention. It is not desired to be limited in its application other than by the scope of the claims which follow:

What I claim is:

1. A process for the conversion of higher boiling oils into lower boiling oils which comprises heating a body of oil under such conditions of 5 temperature and pressure as to effect cracking in the liquid phase, fractionating the generated vapors, releasing the pressure on the reflux condensates resulting from said fractionation to effect separation of vapors from liquid constituents, passing the vapors thus separated through a vapor phase cracking zone, fractionating the products from this zone, and returning to the cracking portion of the liquid phase system the unvaporized portions of the condensates 10 from the first mentioned fractionation after the release of pressure.
2. A process for the conversion of higher boiling oils into lower boiling oils which comprises heating a body of oil under such conditions 20 of temperature and pressure as to effect cracking in the liquid phase, fractionating the generated vapors, releasing the pressure on the refluxed condensates resulting from said fractionation to effect separation of vapors from 25 liquid constituents, passing the vapors thus separated through a vapor phase cracking zone, fractionating the products from this zone and returning to the cracking portion of the liquid phase system the unvaporized portions of the 30 condensates from the first mentioned fractionation after the release of pressure, as well as the refluxed condensates resulting from the second mentioned fractionation.
3. In apparatus of the class described a heating coil, means for applying heat thereto, a drum adapted to receive a body of oil, means for forcing a stream of oil through said coil and into said drum, a dephlegmator for condensing a portion of the vapors generated in said drum, 35 a vaporizer adapted to receive the condensate formed in said dephlegmator, means between said dephlegmator and vaporizer for reducing the pressure on said oil, a second heating coil adapted to receive the vapors from said vaporizer, means for fractionating the products from the last mentioned coil, and means for returning the unvaporized portions from said vaporizer to said first mentioned coil.
4. In apparatus of the class described a heating coil, means for applying heat thereto, a drum adapted to receive a body of oil, means for forcing a stream of oil through said coil and into said drum, a dephlegmator for condensing a portion of the vapors generated in said drum, 50 a vaporizer adapted to receive the condensate formed in said dephlegmator, a heating coil adapted to receive the vapors from said vaporizer, means for fractionating the products from the last mentioned coil, and means for returning the unvaporized portions from said vaporizer and the condensate formed in said fractionating means to said first mentioned coil.
5. A process for the conversion of higher boiling hydrocarbon oils into lower boiling oils 55 which comprises heating oil under such conditions of temperature and pressure as to effect cracking thereof, separating the resulting cracked products into vapors and a liquid residue, fractionating the vapors into light overhead fractions, higher boiling range fractions and intermediate boiling range fractions, returning higher boiling range fractions so obtained to the oil undergoing heating and cracking, heating intermediate boiling range fractions so obtained to a vapor phase cracking temperature to form 10 high anti-knock gasoline fractions, separately fractionating the vaporous products of the last mentioned cracking operation to separate as reflux condensate fractions heavier than the final desired product, separately returning reflux condensate so formed to 15 said oil undergoing heating and cracking for further cracking and condensing the vapors remaining uncondensed after fractionation.
6. A process in accordance with claim 5 wherein in the final desired product is formed by blending 20 said light overhead fractions with the condensate formed by condensing said vapors last mentioned.
7. A process according to claim 5 wherein said light overhead fractions fall mainly in the gasoline boiling range and wherein said intermediate boiling range fractions comprise some gasoline constituents. 25
8. A process according to claim 5 wherein said light overhead fractions fall mainly in the gasoline boiling range and wherein said intermediate boiling range fractions are free from gasoline constituents. 30
9. A process for the conversion of higher boiling hydrocarbon oils into lower boiling oils 35 which comprises heating oil under such conditions of temperature and pressure as to effect cracking thereof, separating the resulting cracked products into vapors and a liquid residue, fractionating the vapors into light overhead 40 fractions, higher boiling range fractions and intermediate boiling range fractions, returning higher boiling range fractions so obtained to the oil undergoing heating and cracking, heating intermediate boiling range fractions so obtained to a vapor phase cracking temperature to form 45 high anti-knock gasoline fractions, separately fractionating the vaporous products of the last mentioned cracking operation to separate as reflux condensate fractions heavier than the final 50 desired product, condensing the vapors remaining uncondensed after fractionation and blending said light overhead fractions with the condensate formed by condensing said vapors last mentioned, to form a final desired product. 55
10. A process according to claim 9 wherein said light overhead fractions fall mainly in the gasoline boiling range and wherein said intermediate boiling range fractions comprise some gasoline constituents. 60
11. A process according to claim 9 wherein said light overhead fractions fall mainly in the gasoline boiling range and wherein said intermediate boiling range fractions are free from gasoline constituents. 65
